DESIGN FOR AN ASBESTOS-CEMENT ROOF SHINGLE OR THE LIKE

George Ritter, Millington, N. J., assignor to The
Ruberoid Co., New York, N. Y., a corporation
of New Jersey

Application July 15, 1939, Serial No. 86,023

Term of patent 14 years

To all whom it may concern:

Be it known that I, George Ritter, a citizen of the United States and a resident of Millington, in the county of Morris and State of New Jersey, have invented a new, original, and ornamental Design for an Asbestos-Cement Roof Shingle or the like, of which the following is a specification, reference being had to the accompanying draw-

ing, forming part thereof, in which the figure is a plan view of an asbestos-cement roof shingle, showing my new design.

I claim:

The ornamental design for an asbestos-cement roof shingle or the like, as shown.

GEORGE RITTER.
